CLAIM

The ornamental design for a coaxial cable connector, as shown and described.

DESCRIPTION

FIG. 1 is a front, top, right-side view of the coaxial cable connector;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines in the drawings illustrate portions of the coaxial cable connector that form no part of the claimed design.
